UNITED STATES PATENT OFFICE

137,235

DESIGN FOR A NEGATIVE ELEMENT FOR SELF-ENERGIZING ELECTROLYTIC WA- TER CORRECTION DEVICES

Edgar M. Butler, New Orleans, La.

Application November 15, 1943, Serial No. 111,693

Term of patent 14 years

To all whom it may concern:

Be it known that I, Edgar M. Butler, a citizen of the United States of America, residing at New Orleans, in the Parish of Orleans and State of Louisiana, have invented a new, original, and ornamental Design for a Negative Element for Self-Energizing Electrolytic Water Correction Devices, of which the following is a specification, reference being had to the accompanying drawing, forming part thereof.

Fig. 1 is a perspective view of a negative element for self-energizing electrolytic water correction devices.

Fig. 2 is a side elevation of the same.

Fig. 3 is a top plan view of the same.

I claim:

The ornamental design for a negative element for self-energizing electrolytic water correction devices, substantially as shown.

EDGAR M. BUTLER.
